UNITED STATES PATENT OFFICE

2,523,704

AUTOMATIC FIREARM BREECH BOLT
LOCKING MECHANISM

Hanns Lippert and Erwin Hepperle, Zurich, Switzerland, assignors to Verwaltungsgesellschaft der Werkzeugmaschinenfabrik Oerlikon, Zurich-Oerlikon, a Swiss company

Application November 5, 1946, Serial No. 707,968
In Switzerland November 7, 1945

17 Claims. (Cl. 89—190)

1

Co-pending application Ser. No. 661,310 discloses an automatic fire-arm with one-piece breech including a pre-tensioned energy accumulator, and in which the locking organ is brought into locked position as soon as the breech has reached its end position.

The present invention now relates to a particularly simple constructional example of the principle disclosed in the above-mentioned co-pending application Ser. No. 661,310. The automatic fire-arm according to the present invention is characterised by the feature that the energy accumulator consists of two parts abutted by the springs serving to accumulate the energy the accumulator being tensioned by levers actuated by the breech block, and that furthermore the lock has a seating in the breech casing. As suitable means for tensioning the energy accumulator, double levers may be provided, seated close to the cartridge chamber and actuated by the breech block on its forward travel as soon as it is close to its forward end position. The action of the energy accumulator on the lock for initiating the locking movement can be intensified by the breech block dealing the energy accumulator a rebound blow. Lastly, the energy accumulator can be designed so that its rear part supports the lock in locked position. The unlocking movement can be started by a gas rod acting, over a double lever, on the rear part of the energy accumulator and removing the latter out of the lock-supporting position, or else levers can be provided, seated on the parts moving to and fro and connected with the rear part of the energy accumulator, which levers, in the course of the rearward travel of the barrel together with the breech casing, hit a stop fitted to the cradle, thus removing the energy accumulator out of the lock-supporting position. The contacting surfaces of the lock with the breech block may be suitably made of such shape that unlocking shall take place automatically on removing the support afforded to the lock by the rear part of the energy accumulator.

The attached drawing shows two constructional examples of the subject of the invention. In this drawing:

Fig. 1 is the schematic set-up of a fire-arm according to a first constructional example in section;

Fig. 2 shows the breech and the organs carrying out the locking operation, during the forward travel of the breech block;

Fig. 3 is a section along line I—I in Fig. 2;

2

Fig. 4 shows the breech block and the organs carrying out the locking operation, as they are just before the breech block reaches its forward end position;

5 Fig. 5 shows the breech block and the organs carrying out the locking operation, in locked position;

Fig. 6 shows the breech block and the organs carrying out the locking operation, on release of the shot, before unlocking;

10 Fig. 7 is the schematic set-up of a fire-arm according to a second constructional example, in section;

Fig. 8 shows the breech block and the organs carrying out the locking operation, during the forward travel of the breech block;

15 Fig. 9 shows the breech block and the organs carrying out the locking operation, in locked position;

20 Fig. 10 shows the breech block and the organs carrying out the locking operation, in the position they occupy upon release of the shot, before unlocking; and

25 Fig. 11 is a top view (part in section) along line II—II in Fig. 10.

In Fig. 1, 1 designates the barrel inserted in the breech casing 2 by means of a bayonet joint 3. The one-piece breech block 4 slides in the breech casing 2 and stands under the action 30 of the recuperating spring 5. 6 is a schematic representation of the trigger mechanism. In the breech casing is fitted the lock 7 in a seating 8 suitably made of hard metal and inserted in the breech casing, the lock being supported on parts 9 and 10 of the energy accumulator. The energy accumulator consists of two parts 35 9 and 10 (Fig. 3) of tubular shape in front seated in the breech casing 2, and two bodies 11 in which are fitted springs 12 driving apart the parts 9 and 10 in relation to the bodies 11 (Fig. 2). Into each of the bodies 11, on both sides of the breech block, there engages a double lever 13, by means of a spherical projection 13a, which double levers are seated in the breech 40 casing 2 close to the cartridge chamber, by means of bolts 14 (see also Fig. 11 of the second constructional example). With the arm 15 the double levers 13 engage the path of noses 4a on breech block 4 and—as represented in Fig. 2—are swung by the breech block 4 on its forward travel. Parts 9 and 10 of the energy accumulator are provided with shoulders 16 (Fig. 4) 45 into each of which engages a spherical projection 17a of a lever 17 seated on the breech cas-

55

ing 2 by means of the bolt 18, and on the arm 19 of which the gas rod 20 acts (Fig. 5).

The bodies 11 on which the levers 13 act and in which are also inserted the springs 12, are fitted with two rods 21 and 22 seated in the breech casing (Fig. 3). These two rods extend with noses 11a beyond the lock 7 and serve to maintain it in position during the rearward and forward travel of the breech block, i. e. in unlocked position.

The lock on which, during the rearward and forward travel of the breech block, the pre-tensioned springs 12 act, and which therefore has the tendency to escape upward, is thus prevented from rubbing (grating) against the breech block moving to and fro, which would tend to lower the firing rate.

The working of the fire-arm just described is briefly as follows: During the forward travel of the breech block the noses 11a of the rods 21 and 22 force downward the lock 7, so that it remains in the position shown in Fig. 2. As soon as the breech block 4 comes near its forwardmost position, it strikes with noses 4a the arm 15 of the double levers 13, swinging them, and thus causing the energy accumulator to take up the tensioned position, as shown in Fig. 4. The rods 21, 22, in accordance with the movement carried out by the levers 13 and transmitted on to the bodies 11, have meanwhile been pulled back, releasing the lock 7. In this position, however, the bodies 11 are in contact with the parts 9 and 10. Therefrom follows that the further forward travel of the breech block, acting by way of the levers 13, causes the bodies 11 and the parts 9 and 10 compulsorily to move together rearwardly. Since the lock-supporting face 4b of the breech block 4 has now allowed the lock to enter, the lock 7 is swung in under pressure through the movement imparted by the breech block to the levers 13 over bodies 11 and parts 9 and 10, the movement being initiated by a rebound blow. The torque causing the lock 7 to rotate is brought about by the fact that the energy accumulator engages the lock 7 by means of slanting faces 9a and 1a. On the breech block 4 reaching its forward reversal position, the lock 7 is cammed upward and catches behind the breech block 4. Parts 9 and 10 of the energy accumulator are now pushed underneath the lock 7—the energy accumulator being at the same time unstressed—thus affording it support.

Upon release of the shot the lever 17 is swung round the bolt 18 by the gas rod 20, and parts 9 and 10 of the energy accumulator pressed forward, tensioning the springs 12, thus depriving the lock 7 of its support by parts 9 and 10. Since the faces 7b and 4b with which the lock 7 contacts the breech 4 are self-unlocking, the lock 7, under the action of the remaining gas pressure, is forced downward, as indicated by an arrow in Fig. 6, and consequently the breech block 4 unlocked, so that—under the action of the remaining gas pressure forces—it can be driven back against the recuperating spring 5. The self-unlocking action is due to the fact that the direction of the force transmitted by the breech block to the lock 7 forms with the straight line connecting the center of the force-transmitting area of the engaging surfaces 4b, 7b, and the fulcrum of the lock, an angle which is greater than the angle of friction, so that upon removal of the underlapping portions of the parts 9 and 10 of the energy accumulator from under the lock, unlocking occurs automatically.

Under the action of the springs 12, tensioned

anew as described above, the levers 13 now take up the position shown in Fig. 2, the rods 21 and 22 catching with noses 11a over shoulders 1c on the lock 7 (Fig. 11), thus holding the lock in position.

In Figs. 7-11 is shown a further constructional example for the return of the parts 9 and 10 of the energy accumulator, for the purpose of removing the support of the lock 7, all other parts, however, remaining the same. The breech casing 2 is fitted laterally with two fork-shaped levers 23, seated in the casing by means of bolts 24. The fork-shaped levers 23 are fixed to parts 9 and 10 of the energy accumulator by means of pivots 25 (Fig. 11). The levers 23 are provided with cams 26, whilst a stop 28 is fitted on the cradle 27.

Upon release of the shot, the barrel 1 and the breech casing 2 move backward, so that the cams 26 of the levers 23 strike the stop 28 of the cradle 27, thus keeping back the parts 9 and 10 of the energy accumulator, and depriving the lock 7 of its support through parts 9 and 10. All other parts are the same as in the constructional example according to Figs. 1-6.

We claim:

1. Automatic fire-arm comprising a breech casing, a one-piece breechblock slidable therein, means mounted in the breech casing for locking the breechblock against movement relative to the casing, mechanism for bringing the locking means into locking position and comprising a pre-tensionable energy accumulator having two parts and a spring acting on said parts and serving to accumulate the energy, and mechanism actuated by the breechblock for tensioning the energy accumulator.

2. Automatic fire-arm according to claim 1, wherein the breech casing is provided with a cartridge chamber and wherein the tensioning mechanism comprises a double lever mounted close to the cartridge chamber and actuated by the breechblock on its forward travel close to its front reversal position.

3. Automatic fire-arm according to claim 1, wherein the rear portion of the energy accumulator is arranged to catch underneath the locking means to hold it in locked position.

4. Automatic fire-arm according to claim 1, wherein the rear portion of the energy accumulator bears against the locking means in its inoperative position by way of inclined cam surfaces which act to move the locking means into locking position when said means are released.

5. Automatic fire-arm according to claim 1, including a lever actuated by the breech block on its forward movement and arranged to move one part of the energy accumulator rapidly toward the other and to engage the same with sudden impact with tensioning of the spring fitted between them, whereby the movement imparted by the breech block to said lever is transmitted on to the locking means with sharp impact pressure.

6. Automatic fire-arm according to claim 1, including a gas rod for initiating the unlocking motion, and a double lever acting on the rear part of the energy accumulator and operated by the gas rod to remove said rear part out of the position in which it holds the locking means in operative position.

7. Automatic fire-arm according to claim 1, including a cradle for slidably supporting the breech casing, a stop on the cradle, and a lever pivoted on the breech casing and connected with the rear part of the energy accumulator, said

lever being so disposed that during the rearward travel of the breech casing, it strikes said stop and is rotated so as to remove the energy accumulator out of the position in which it holds the locking means in operative position.

8. Automatic fire-arm according to claim 1, wherein the front part of the energy accumulator is provided with a rod supported in the breech casing and acting to keep the locking means in the unlocking position.

9. Automatic fire-arm comprising a cradle; a breech casing slidable on the cradle; a breech block slidable in the casing; and means for locking and releasing the breech block and comprising a locking member seated in the breech casing and normally disposed out of the path of the breech block, and an energy accumulator including a front part, a rear part, and a compression spring disposed between said parts, the rear face of the rear part engaging the locking member along inclined surfaces of such shape that the locking member is urged into locking position, a rod connected with the front part and normally overlying the locking member to hold the same in inoperative position, means actuated by the breech block on its forward travel to shift the front part of the energy accumulator to cause release of the locking member and to compress said spring, whereupon said locking member is urged into locking position by the rear part of the accumulator under the action of said spring.

10. Automatic fire-arm according to claim 9, including means actuated by the pressure of the explosion gases in the barrel to shift the rear part of the accumulator forwardly to release the locking member.

11. Automatic fire-arm according to claim 9, wherein the locking member is shaped to receive the rear portion of the rear part of the accumulator beneath it when it has been shifted into locking position, whereby the locking member is locked in locking position.

12. Automatic fire-arm according to claim 9, wherein the locking member engages the breech block along inclined surfaces which cam the locking member into unlocking position upon release of the locking member and under the action of the gas pressure on the breech block.

13. Automatic fire-arm according to claim 9, including mechanism operative after the firing of the shot to move the rear part of the accumulator forwardly to release the locking member.

14. Automatic fire-arm according to claim 9, wherein an energy accumulator is disposed upon opposite sides of the breech block.

15. Automatic fire-arm comprising a cradle; a breech casing slidable on the cradle; a breech block slidable in the casing; and means for lock-

ing and releasing the breech block and comprising a locking member supported on the breech casing and normally disposed out of the path of the breech block, and a floating energy accumulator

5 including a front part and a rear part movable relative to each other and both slideable in the casing, and a compression spring disposed between said parts, said parts being movable by the breech block as it approaches its forward reversal position to release the locking member and move it into locking position.

16. Automatic fire-arm according to claim 1, wherein the locking means comprises a pivoted member swingable into and out of locking position, the energy accumulator including a portion 15 underlapping the locking means in the operative position of the latter to hold the locking means in such operative position, and wherein the surfaces along which the locking means and breech 20 block engage are inclined in such manner that the direction of the force transmitted by the breech block to the blocking means forms with the straight line connecting the center of the force-transmitting area of said surfaces and the fulcrum of the locking means an angle which is greater than the angle of friction, so that upon removal of the said underlapping portion, unlocking occurs automatically on rearward travel of the breech block.

17. Automatic fire-arm according to claim 1, wherein the energy accumulator includes a portion 30 underlapping the locking means in the operative position of the latter to hold the locking means in such operative position, and wherein 35 the faces along which the locking means and the breech block engage each other are inclined to the direction of rearward travel of the breech block to such a degree that upon removal of the underlapping portion of the energy accumulator from under the locking means, the latter is automatically cammed out of locking position by the rearwardly traveling breech block.
